(57) **CLAIM**

The ornamental design for a shrink wrap gun for plastic film, as shown.

DESCRIPTION

FIG. 1 is a side view of a shrink wrap gun for plastic film according to my new design;

FIG. 2 is a front view thereof;

FIG. 3 is a rear view thereof;

FIG. 4 is a three-quarter rear perspective view thereof;

FIG. 5 is a bottom view thereof;

FIG. 6 is a top view thereof; and,

FIG. 7 is a three-quarter front perspective view thereof.

The features shown in broken lines are not part of the claimed design.
